UNITED STATES PATENT OFFICE.

HENRY BODENSTEIN, OF ARLINGTON, MASSACHUSETTS.

ICE-PLANER.

SPECIFICATION forming part of Letters Patent No. 670,698, dated March 26, 1901.

Application filed May 7, 1900. Serial No. 15,722. (No model.)

To all whom it may concern:

Be it known that I, HENRY BODENSTEIN, a citizen of the United States, residing at Arlington, in the county of Suffolk and State of Massachusetts, have invented certain new and useful Improvements in Ice-Planers, of which the following is a specification, reference being had therein to the accompanying drawings.

10 My invention relates to improvements in ice-planers, and refers particularly to planers such as are employed in connection with elevators used for carrying ice to the warehouse or ice-storage house.

15 One object of my invention is the provision of an ice-planer which will reduce the ice to an even thickness under all circumstances and which can be adjusted to plane or smooth the surface of the ice or to form grooves or 20 corrugations on the surface thereof, as desired and necessary.

25 Another object of my invention is the provision of an ice-planer which can be quickly adjusted to plane the ice and which will be retained firmly and reliably at the desired adjustment under the heavy and severe strain to which it is subjected.

30 Another object of my invention is the provision of an ice-planer which will be light in weight and which can be operated perfectly by a single attendant, thus dispensing with the amount of labor usually found necessary and avoiding the placing of severe hardship upon the attendant or attendants, as has heretofore been the case.

35 Another object of my invention is the provision of an ice-planer for use in connection with ice-elevators which will be superior in points of simplicity, durability, and inexpensiveness and which will be thoroughly efficient and practical.

40 To attain the desired objects, my invention consists of an ice-planer embodying novel features of construction and combination of parts, substantially as disclosed herein.

45 In order that the details of construction of my ice-planer and its operation may be readily understood and its numerous advantages be fully appreciated, I have illustrated in the 50 accompanying drawings a machine constructed in accordance with and embodying my invention.

Figure 1 represents a side elevation of my ice-planer with a sufficient portion of an elevator to show the relation or combination of 55 my planer to the elevator. Fig. 2 represents a central sectional view, a series of cakes of ice being shown upon the endless carrier and the carriage with knives being shown in full lines in operative position and in dotted lines 60 out of operative position. Fig. 3 represents a detail view, on an enlarged scale, of a portion of the carriage, guide-frame, and rack and shoe with cutters. Fig. 4 represents a perspective view of the ice-planer and a portion of the elevator, and Fig. 5 represents a detail view of the shoe with planer or knife applied and detached to show the manner of applying knives or cutters.

Referring by numerals to the drawings, in 70 which similar numerals of reference denote corresponding parts in the several views, the numeral 1 designates a portion of an elevator, such as usually employed for elevating and conducting ice to storage-houses and which is 75 provided with an endless carrier 2, which is operated in any manner and delivers the ice to the ice-house.

The framework of my planer, which is 80 reliably secured to the elevator, consists of the vertical supports 3 and the horizontal rails 4, which frame is made of the proper dimensions and is strong, though light in weight. To the rails are rigidly secured the rack-bars 5, with which engage the gear-wheels 6, carried by the transverse shaft 7, which at one end carries the hand-wheel 8, the purpose of 85 which is to revolve the shaft and move the carriage 9, in which shaft 7 is journaled.

The carriage 9 is provided with guides or 90 cleats 10, which fit upon the horizontal rails, and the guide on one side of the carriage is provided with a dog or detent 11, which engages one of the gear-wheels and retains the carriage at any point of adjustment along the 95 rack-bars, and to prevent the carriage from accidental movement or displacement by reason of the very heavy strain I provide the adjustable stops or abutments 12, which embrace and bite against the rails, as clearly 100 shown, each of said stops being in the form of a clamp or vise. To the carriage are connected the shoes 13, one end being pivoted or swung at 14 and the other end at the upper

portion being provided with slots 15, in which fit adjusting-screws 16, with nuts 17, by which construction it will be seen that the planers 18 or the corrugating-knives 19 may be adjusted and held by the clip 20 to the bars 21, which are secured to the shoes.

It will be understood that the planers are used with the cutter-bars when it is desired to smooth the surface of the ice and that the fluted knives are used when it is necessary to corrugate or groove the face of the ice.

The operation of my ice-planer will be readily understood from the foregoing description, taken in connection with the accompanying drawings, and it will be apparent that the carriage is adjusted to the proper and desired point on the rack-bars according to the size of the blocks of ice and also to the thickness which it is desired to remove from the ice, and when the proper and desired adjustment has been obtained the elevator brings the cakes of ice against the first knife or planer and a portion of the surface is removed, and then the cakes are brought against the second knife or planer and the finishing of the planing is accomplished, the ice then being conveyed in the proper size and shape to the ice-house and stored therein.

The advantages of my machine will be readily understood by all skilled in the ice business, and it will be seen that the ice may be planed or corrugated and any amount of the ice removed as circumstances require and the work accomplished rapidly and perfectly. It will also be noted that the machine can be easily and quickly adjusted to the work and remain in that position, and thus dispense with the constant attention of an operator and also avoid the heavy work which is now thrown upon the attendant. It will also appear that my machine is extremely simple in construction and can be produced at a very low figure and also that it is light and compact in weight, but sufficiently strong to withstand the hardest strain and the damaging influences to which such machines must be subjected.

I claim—

1. The combination with an inclined ice-elevator, of a horizontally-disposed frame, horizontally-disposed rack-bars on said frame, a carriage movable on said frame and having gear-wheels engaging said rack-bars, cutters carried by said carriage, means engaging one of said gear-wheels to hold the carriage in its adjusted position and stops for limiting the adjustment of the carriage, as set forth.

2. The combination of the frame composed of the vertical supports and the longitudinal rails, rack-bars secured to the rails, a carriage

carrying gear-wheels engaging the rack-bars for moving the carriage, a dog or pawl engaging one of said gear-wheels to hold the carriage at any adjustment, stops or abutments to limit the travel of the carriage, adjustable 65 shoes carried by the carriage and having cross-bars provided with means for securing the knives or planers.

3. The combination with an inclined ice-elevator, a frame connected therewith horizontally disposed, rack-bars secured to said frame, a carriage mounted on the frame, gears carried by the carriage and meshing with the rack-bars, means for securing the carriage at any adjustment on the rack-bars, shoes connected to the carriage one being pivoted and the other adjustable and cutters or planers secured to and carried by the shoes. 70 75

4. In an ice-planer, the combination with an inclined ice-elevator, of the horizontal 80 frame, a carriage mounted upon and traveling on the horizontal frame, devices for retaining the carriage at any desired adjustment upon said frame, adjustable shoes carried by said carriage, and cutters mounted in 85 the shoes.

5. In an ice-planer, the combination with an inclined ice-elevator of a horizontal frame supported thereon, rack-bars secured to the horizontal frame, a shaft carrying gear-wheels 90 which engage with said rack-bars, a carriage supported upon said shaft, devices for holding the carriage at any place upon the rack-bars, means for limiting the travel of the carriage, shoes secured to the carriage and carrying a series of cutters. 95

6. In an ice-planer, the combination with an inclined elevator, the frame composed of the vertical standards and the horizontal side rails, the carriage mounted on the side rails 100 and adapted to move thereon, means for holding the carriage at any desired adjustment and means for regulating the travel of the carriage, adjustable shoes carried by the carriage, and cutters mounted in said shoes. 105

7. In an ice-planer, the combination with an inclined elevator, the frame having the horizontal rack-bars, the carriage having the gear-wheels engaging the rack-bars, the pivoted dogs or pawls for retaining the carriage 110 at any point on the rack-bars, the adjustable stops for limiting the movement of the carriage, the pivoted adjustable shoes in the carriage and the cutters carried by the shoes.

In testimony whereof I affix my signature 115 in presence of two witnesses.

HENRY BODENSTEIN.
